United States Patent Office

Des. 228,660

Patented Oct. 16, 1973

228,660

VEHICLE COMMUNICATIONS AND CONTROL CONSOLE

Don W. Noren, Redwood City, Calif., assignor to Noren
Products, Inc., Redwood City, Calif.

Filed May 10, 1971, Ser. No. 142,117

Term of patent 14 years

Int. Cl. D14—03

U.S. Cl. D26—14 K

FIG. 1 is a front view of a vehicle communications and control console, showing my new design;

FIG. 2 is a bottom plan view taken on line 2—2 of FIG. 1;

FIG. 3 is a side elevation taken on line 3—3 of FIG. 1;

FIG. 4 is a side elevation taken on line 4—4 of FIG. 1;

FIG. 5 is a rear view taken on line 5—5 of FIG. 3;

FIG. 6 is a top plan view taken on line 6—6 of FIG. 1.

I claim:

The ornamental design for a vehicle communications and control console, as shown and described.
